UNITED STATES PATENT OFFICE.

ALLEN LOOMIS, OF DETROIT, MICHIGAN, ASSIGNOR TO PACKARD MOTOR CAR COMPANY, OF DETROIT, MICHIGAN, A CORPORATION OF MICHIGAN.

DETACHABLE LIGHT FOR VEHICLE-CURTAINS

1,125,352.

Specification of Letters Patent. Patented Jan. 19, 1915.

Application filed November 8, 1909. Serial No. 526,831.

To all whom it may concern:

Be it known that I, ALLEN LOOMIS, a citizen of the United States, and resident of Detroit, county of Wayne, State of Michigan, have invented certain new and useful Improvements in Detachable Lights for Vehicle-Curtains, of which the following is a specification.

This invention relates to curtains for vehicles, and especially to those used in connection with motor vehicles.

It is desirable at times to roll up the vehicle curtains and move them out of the way, this being generally accomplished by rolling them up and securing them in position underneath the roof of the vehicle. Since these curtains are generally provided with lights, it is desirable that the latter may be detachably secured to the curtain body, so that they may be removed when the curtain is rolled up, or readily replaced when broken or scratched.

The object of this invention, therefore, is to construct a curtain in which the light may be quickly removed and again secured in place.

In the drawings: Figure 1 is a view of a curtain, showing the invention applied thereto. Fig. 2 is an enlarged view, showing the section of the curtain immediately surrounding the light. Fig. 3 is a section on the line 3—3 Fig. 2. Fig. 4 is a section on the line 4—4 Fig. 2, and Fig. 5 is a view of the reversed side of the curtain from that shown in Figs. 1 and 2.

Referring to the drawings, 10 designates a curtain body provided with an opening 11. A plurality of strips 12 and 13 are secured to the curtain body by means of rows of 40 stitches 14, forming together a pocket. A plurality of snap fastener sockets 15 are secured to the curtain body, and extend through the strip 12. The strip 13 has secured thereto a plurality of heads 16, which 45 coöperate with the sockets 15. The rows of stitches 14 extend through both of the strips 12 and 13 to points designated 17, 17 on Fig. 5. This construction leaves the right-hand end 18 of the upper strip free, so as to 50 form a swinging flap. A suitable light 19,

provided with a number of holes 20, is adapted to be placed in the pocket formed by the strips 12 and 13, the holes 20 alining with the snap fasteners. The light 19 is preferably flexible, and may be composed of 55 celluloid, or any other flexible transparent material.

The light is secured in place by separating all of the coöperating heads 16 and sockets 15, and inserting it in place in the 60 pocket formed by the strips 12 and 13, by separating the flap 18 from the body of the curtain, as shown in Fig. 3. After the light is in place the heads 16 are all snapped into locking engagement with the coöperating 65 sockets 15, and the light will thus be securely held in place. Whenever it is desirable to roll up the curtain or replace a broken or scratched light the light is removed by disengaging the heads 16 from the 70 sockets 15, and removing the light from the pocket through the open end formed by separating the flap 18 from the body member.

It is obvious that various changes may be 75 made in the details of construction without departing from this invention, and it is, therefore, to be understood that this invention is not to be limited to the specific construction shown and described. 80

Having thus described my invention, what I claim is:—

1. The combination with a vehicle curtain provided with an opening and a light therefor, of a flexible strip around the opening 85 secured to the curtain and forming with the curtain a pocket adapted to receive said light, a part of said strip being free from the curtain to permit the light to be inserted into and removed from the pocket, and 90 snap fasteners comprising coöperating parts secured respectively to the curtain and said strip for connecting the free portions of the strip with the curtain to secure the light in the pocket. 95

2. The combination with a vehicle curtain provided with an opening and a light therefor having marginal openings therein, of a flexible strip around the opening secured to said curtain and forming with the curtain a 100

5 pocket adapted to receive said light, a part of said strip being free from the curtain to permit the light to be inserted into and removed from the pocket, and snap fasteners comprising coöperating parts secured respectively to the curtain and said strip, some of said parts extending through the marginal openings in the light and connecting the

free portions of the strip with the curtain to secure the light in the pocket.

10 In testimony whereof I affix my signature in presence of two witnesses.

ALLEN LOOMIS.
